UNITED STATES PATENT OFFICE.

THORSTEN NORDENFELT, OF WESTMINSTER, ENGLAND.

PROJECTILE.

SPECIFICATION forming part of Letters Patent No. 270,101, dated January 2, 1883.

Application filed September 11, 1882. (No model.) Patented in England February 23, 1882, No. 891, and in France May 16, 1882, No. 149,008.

To all whom it may concern:

Be it known that I, THORSTEN NORDENFELT, a subject of the King of Sweden, residing at 53 Parliament Street, in the city of Westminster, England, have invented a certain new and useful Improvement in Projectiles, (for which I have received Letters Patent in Great Britain, No. 891, dated 23d February, 1882, and in France, No. 149,008, dated 16th May, 1882,) 10 of which the following is a specification.

The object of my invention is to improve projectiles of iron or steel—such as are coated or covered with a softer metal—for the following special purposes: first, to prevent by means of the softer metal the hard projectile from damaging or wearing out the grooves of the rifling; second, to use a projectile closer up to the gage of the caliber of a gun than can be done if the hard metal is without such softer covering, as 15 the projectiles might stick in the bore and cause an explosion; third, to insure better centering of the projectile in the bore, and consequently a steadier flight through the air, than can be attained with the larger play, which is necessary if the projectile is not covered with softer metal; fourth, to give required rotation to the projectile by means of the softer-metal covering by letting it into the grooves of the rifling. In order to do this, I make the part or parts of 20 the surface of the iron or steel projectile which have to be coated with the softer metal sufficiently even or polished, and I clean these parts by dipping the projectile into acid. Then I insert the projectile into a bath of copper or tin, 25 and apply electricity from a galvanic battery or from an electrical machine. By this means I cause copper or tin to be deposited on and to adhere to the surface of the projectile to the desired thickness. To cause the coating of 30 copper or tin to give rotation to the projectile, I make it thicker in one or more parts of the projectile than in the other parts; or I put a disk or one or more rings of copper or brass round the projectile of such a diameter as to 35 fill up the bore completely, and then put on the coating over this disk or rings by means of the copper or tin bath. The coating put on in the copper or tin bath assists in fixing this disk or rings onto the projectile. If I wish to put a partial covering, only onto the projectile, I cover 40

the remaining parts with a suitable varnish to prevent the electro-deposit taking place on the parts which I do not wish to have coated with copper or tin. When I wish to have the coating or covering of softer metal thicker in some parts than in others I put the coating on first of the required thickness over the whole projectile or over the parts which I wish to have thinly covered. Then I put varnish over the parts I wish thinly covered, and put the projectile 45 again into the electrical bath and apply a thicker covering to the unvarnished parts.

In order that my said invention may be most fully understood and readily carried into effect, I will proceed to describe the drawings 50 hereto annexed.

In the drawings, Figure 1 is a longitudinal section of an iron or steel projectile coated with copper or soft metal in accordance with my invention. *a* is the body of the projectile. *b* is 55 a cup of the softer metal deposited upon or applied to the base of the projectile. It is intended to take the rifling and impart rotation as the projectile travels along the barrel. *c* is a covering of the softer metal applied over the 60 cup. If it be desired to produce the cup *b* by deposition from a coating-bath, the projectile, having been thoroughly cleaned, is immersed in the coating-bath to the depth to which it is desired that the deposit should extend, the 65 electrical connections are made, and the metal deposited from the solution until it attains the requisite thickness; or the surface may be varnished, excepting those parts on which the cup is to be produced, and then the projectile may 70 be more deeply immersed in the coating-bath. When a cup of the desired thickness is formed the projectile is removed from the bath and the varnish is thoroughly cleaned off before the next operation; or, in place of producing the 75 cup by electrical deposition, a cup of the softer metal, produced by casting or stamping, may be forced onto the base end of the projectile. The cup having been formed or applied, the outer covering, *c*, is then produced over it by electrical deposition, as already described in respect to the cup *b*. The covering *c* extends over 80 all the parts of the projectile which can come into contact with the interior of the barrel.

Fig. 2 represents a section of a projectile in 85

which a base-cup is not employed; but in place thereof there are rings of the softer metal to take the rifling. *d d* are these rings. They may be produced by electric deposition, while the other parts of the surface of the projectile are covered with varnish; or they may be rings cut from a tube of the softer metal and forced onto the body of the projectile. The outer covering, *c*, is produced over the rings, as also ready described.

Fig. 3 is a section of a projectile similar to that shown by Fig. 2, but furnished both with base-cup and ring.

Fig. 4 is a section of a projectile which has first received a thin coating of the softer metal by electrical deposition sufficient to protect the

projectile from rust, and which has then been provided with a base-cup, *b*, and an outer covering, *c*, by the means already described.

Having thus described the nature of my said invention and the manner of performing the same, I would have it understood that I claim—

A hard-metal projectile provided with the soft-metal base-cup or specified equivalent thereof, and with the outer envelope or covering of soft metal, as and for the purpose described.

THORSTEN NORDENFELT.
